APPARATUS FOR RAILWAY TRAIN COMMUNICATION SYSTEMS

Leland D. Whitelock, Wilkinsburg, and Paul N. Bossart, Cheswick, Pa., assignors to The Union Switch & Signal Company, Swissvale, Pa., a corporation of Pennsylvania

Application May 2, 1936, Serial No. 77,576

9 Claims. (Cl. 246—8)

Our invention relates to apparatus for railway train communication systems, and has for an object the provision of novel and improved track-way apparatus for use in systems for communication between two spaced locations on a train, or between two different trains, or between a wayside station and a train.

We will describe three forms of apparatus embodying our invention, and will then point out the novel features thereof in claims.

In the accompanying drawing, Fig. 1 is a diagrammatic view of one form of apparatus embodying our invention wherewith existing line wires employed in a wayside signal system are made to form a channel for transmitting communication current along a railway. Fig. 2 is a diagrammatic view of a second form of apparatus embodying our invention wherewith existing line wires of a wayside signal system are made to form a channel for communication current. Fig. 3 is a diagrammatic view of apparatus embodying our invention wherewith a line which extends continuously along a stretch of railway is made to form a channel for communication current.

In each of several views, like reference characters designate similar parts.

Referring to Fig. 1, the reference characters $1a$ and $1b$ designate the track rails of a railway track and which are divided by the usual insulated rail joints 2 to form successive track sections, two full sections A — B and B — C and the ends of the two sections adjacent thereto being shown in Fig. 1. These track sections are those provided for the usual wayside signal system, and it will be understood the entire railway may be divided into consecutive track sections, the junction of each two sections being a signal location for the apparatus of a wayside signal system. The reference characters $L1$, $L2$, $L3$, and $L4$ designate line wires each of which forms one side of a signal control circuit extending the length of the associated track section and terminating in wayside signal apparatus at the associated signal locations. For example, these line wires may each form one side of an approach lighting circuit for a wayside signal system. Looking at location B of Fig. 1, the relay 30 may be an approach lighting relay controlled over a control circuit including a contact 61 of a track relay (not shown) at location A and the line wire $L2$. The remaining portion of these signal control circuits is not shown for the sake of simplicity since such circuits form no part of our invention. The significant feature

about these line wires $L1$, $L2$, $L3$ and $L4$ in connection with the present invention is the fact that they provide a sectionalized line wire extending the full length of a designated stretch of railway.

To form these successive line wires into a communication channel which may be utilized for transmitting a communication current along the railway independent of the wayside signal system and without interference in any way with the wayside signal system, we provide a track circuit network and a circuit connection at selected points. Through the medium of such track circuit networks and circuit connections, each individual line wire and the rails of the associated track section in multiple are made to form a closed circuit, and the successive circuits thus formed are coupled together to provide a channel effective to transmit the communication current. When a track circuit network and circuit connection are placed at a signal location, the network ordinarily spans the insulated rail joints at that location. It will be understood, however, that a track circuit network and circuit connection may be placed at locations other than at insulated rail joint locations if desired. These track circuit networks and circuit connections are proportioned and adjusted to tune the circuits formed thereby and to reduce the characteristic impedance as low as practicable at the frequencies of the communication current without endangering the integrity of the wayside signal circuits nor giving an excessive value of attenuation to the line wire and circuit connections.

Looking at location A of Fig. 1, the circuit network comprises two resistors 3 and 4 , resistor 3 being connected across the rails at the right-hand side of the insulated rail joints 2 , and the resistor 4 being connected across the rails at the left-hand side of the insulated rail joints. The mid-terminal of resistor 3 is connected with line wire $L2$ extending to the right from location A by a circuit connection including wire 5 , condenser 6 , and wire 7 . In like manner, a circuit connection including wire 8 , condenser 9 , and wire 10 connects the mid-terminal of resistor 4 to the line wire $L1$ extending to the left from location A . The resistors 3 and 4 are each proportioned to substantially match the characteristic impedance of the rails at the frequency of the communication current, and at the same time not impair the wayside signal circuits. For example, the communication current may be a carrier telephone current of 7500 to 9500 cycles per second. That is,

the telephone current may be the upper side band of a carrier of 7000 cycles modulated at voice frequencies extending from 500 to 2500 cycles per second. We have found that resistors 3 and 4, 5 when of about 10 ohms each, will substantially match the characteristic impedance of the rails at the frequency range cited above under the usual ballast resistance conditions. Such resistors are also large enough to not seriously interfere 10 with the usual track circuits of the wayside signal system. Condensers 6 and 8 interposed in the circuit connections when made about 0.25 microfarad are satisfactory to efficiently tune at the frequency of the communication current a line 15 wire which forms one side of a signal control circuit for a typical block length.

At location B of Fig. 1, the circuit network is similar to that just described for location A except the resistors 13 and 33 which are connected 20 across rails at the opposite sides of the insulated rail joints, are joined at their mid-terminals by a conductor 34. The mid-terminal of resistor 13 is connected with line wire L2 extending to the left from location B over a connection including 25 wire 36, condenser 12, and wire 11; and the mid-terminal of resistor 33 is connected with line wire L3 over a circuit connection including wire 38, condenser 40, and wire 41.

At location C, the track circuit network and circuit connections for connecting the line wires L3 and L4 with the track rails of the respective track sections are the same as at location B except for the fact a condenser 35 is interposed in the conductor 37 joining the mid-terminals of the resistors 39 and 43. It is to be seen that each track 30 section of Fig. 1 is provided with a closed circuit one side of which is formed by the two track rails in multiple, and the other side of which is formed by a line wire. Hence, carrier telephone current supplied to the two rails of section A-B 35 in multiple flows in a circuit that may be traced from the point where it is supplied to the rails to resistor 3, the two portions of resistor 3 to its mid-terminal, wire 5, condenser 6, wire 7, line 40 wire L2, wire 11, condenser 12, wire 36 to the mid-terminal of resistor 13, the two portions of resistor 13 to the track rails 1a and 1b, and, thence, to the starting point. Likewise, a similar circuit may be traced for section B-C, and for each 45 of the remaining sections of the railway.

Assuming a communication current of the frequency range explained hereinbefore is supplied to the track rail of section A-B and flows in the circuit just traced for that section, during one-half cycle of the current, the potential of the mid-terminal of resistor 13 is above ground potential, and during the other half cycle, its potential is below ground potential due to the distributed ballast resistance of the track rails. 50 Communication current is transferred from the above-traced circuit of section A-B to the circuit for the section B-C by virtue of the variations in the potential of the mid-terminal of resistor 13 with respect to ground potential. For example, when the potential of the mid-terminal of resistor 13 is above ground potential, current flows over conductor 34 to the mid-terminal of resistor 33, and, thence, to ground over two parallel paths one of which includes wire 38, condenser 40, wire 41, line wire L3, circuit connection including condenser 42 at the right-hand end of section B-C, the two portions of resistor 39, and the rails of section B-C serving as a ground electrode. The other path includes the two portions of resistor 33 and the rails of section B-C serving as a 55 75

ground electrode. During the other half cycle of the current, current flows from ground to the mid-terminal of resistor 13 through the medium of the circuit of section B-C. Hence, communication current supplied to the rails of section A-B 60 flows in a permanently closed circuit of which the line wire L2 forms the return side of the circuit, and communication current is transferred to the rails of the section B-C through the medium of the corresponding circuit for that section. The 65 current thus transferred is available for influencing receiving apparatus coupled with the track rails of section B-C. Because of the frequency range of the communication current and due to the proportioning of the parts of the closed 70 circuits of the respective track sections, the wayside signal circuits associated with these track sections are not effectively influenced. It is to be noted that at location A, transfer of communication current from the section A-B to the section 75 to the left of location A takes place when the insulated rail joints at location A are short circuited by a train. At location C, the condenser 35 interposed in the track circuit network 80 tunes the track to maximum efficiency of the 85 frequency range of the communication current. This condenser should be about two microfarads.

Three different forms of track circuit networks are disclosed in Fig. 1, and it will be understood that any one of these three forms may 90 be provided at each signal location, if desired. It is to be noted that at a location other than an insulated rail joint location the track circuit network would consist of a single resistor such as resistor 3 at location A, and its mid-terminal 95 would be connected with the line wires leading in each direction from that location over a circuit connection similar to those described for Fig. 1.

In Fig. 2, the track rails 1a and 1b are divided 100 into track sections the same as in Fig. 1, three full sections A1-B1, B1-C1, and C1-D1 being shown in the drawing. The line wires L5, L6, L7, L8, and L9 are each one side of a signal control circuit associated with the respective track 105 sections. For example, these line wires may each be included in an approach lighting control circuit 110 the same as in Fig. 1. The adjacent ends of these respective line wires are joined through 115 two condensers connected in series. For example, at location A1, line wires L5 and L6 are connected through condensers 17 and 18 in series. 120 These condensers 17 and 18 are included in the circuit connection which connects the line wires L5 and L6 with the track circuit network at that 125 location. Three possible arrangements for the track circuit network are disclosed in Fig. 2. At 130 location A1, the resistors 14 and 15, which are connected across the track rails at the opposite sides of the insulated rail joints, are joined at 135 their mid-terminals by a conductor 16. The mid-terminal of condensers 17 and 18 is connected with the conductor 16 over a circuit connection 140 including wire 19, condenser 20, resistor 21, and wire 22. At location B1, the track circuit network is the same as at location A1 and includes 145 resistors 23 and 24 connected across the rails of the respective track sections, and a conductor 25, joining the mid-terminals of resistors 23 and 24. The mid-terminal of condensers 23 and 27 150 at location B1 is connected with the conductor 25 of the track circuit network over a connection 155 including wire 28, resistor 29, and wire 30. At location C1, the arrangement is the same as at 160 location A1, except a condenser 44 is interposed 165

in the conductor joining the mid-terminals of the resistors connected across the rails. At location D₁, the arrangement differs from that at location C₁ in that two condensers 31 and 32 are serially 5 interposed in the conductor joining the mid-terminals of the resistors connected across the rails, and the circuit connection by which the line wires L₈ and L₉ are connected with the track circuit network is connected at the mid-terminal 10 of condensers 31 and 32.

It is to be seen that each track section of Fig. 2 is provided with a permanently closed circuit which includes the two rails in multiple as one side of the circuit, and the associated line wire 15 is the other side of the circuit. In this form of the invention, the resistors connected across the track rails are proportioned to match the characteristic impedance of the rails at the frequency of the communication current the same as in 20 Fig. 1. The condensers interposed in series with the sectionalized line wire are each proportioned to series tune the line wire and are each about 0.25 microfarad in a typical case. We have found that when series tuning is employed, two condensers one at each end of the line wire are more 25 effective than where only one condenser is provided. The arrangement in Fig. 2 differs from that of Fig. 1 in that the resulting communication channel consisting of the sectionalized line wire as one side and the track rails as the other side, is loaded to reduce its characteristic impedance to more nearly match the rails by virtue 30 of coupling condensers and/or resistors. For example, condenser 20 at location A₁ is proportioned to load the two circuits extending in the opposite directions from that location to reduce 35 their characteristic impedance, and it is also effective to couple the two circuits. At location B₁, the resistor 29 is proportioned to reduce the 40 characteristic impedance of the circuits extending in opposite directions from that location, and it also serves as a coupling unit between the two circuits. The condenser 20 should be about one 45 microfarad and the resistor 29 should be about 30 ohms. The resistor 21 at location A₁ and resistors 54 and 55 at locations C₁ and D₁, respectively, are provided to avoid a possible false operation 50 of the wayside signal system in the case of a broken rail. A value of 10 ohms has been found satisfactory for these resistors in conjunction with a circuit condenser or condensers.

Communication current supplied to the track rails of section A₁—B₁ in multiple flows in a circuit which may be traced to the left from the point where the current is supplied to the rails, the two portions of resistor 15 to its mid-terminal, wire 22, resistor 21, condenser 20, wire 19, condenser 18, line wire L₆, condenser 26, wire 28, resistor 29, wire 30, conductor 25 to the mid-terminal of resistor 23, the two portions of resistor 23 to the rails 1a and 1b, and back to the original point. Due to communication current flowing in this circuit, the potential of the mid-terminal of resistor 23 varies with respect to 65 ground potential and communication current is transferred to the circuit associated with the section B₁—C₁ in the same manner as described for Fig. 1. In addition, the voltage drop across resistor 29 also causes communication current to 70 flow in the closed circuit associated with the section B₁—C₁. Consequently, communication current supplied to the rails of section A₁—B₁ is transferred to the corresponding circuit associated with section B₁—C₁ and, in turn, to the corresponding circuits of the sections more remote. 75

In Fig. 3, the track rails 1a and 1b are inserted into track sections A₂—B₂ and B₂—C₂. Track circuit networks are provided at each of the locations A₂, B₂, and C₂. As here shown, these networks are each similar to the network provided at location D₁ of Fig. 2, and it is thought to be unnecessary to repeat their description in detail. In this case, the line wire L₁₀ is common to all track sections and does not terminate at each signal location. The line wire L₁₀ may, for 10 example, be one side of an existing power line common to all signal locations of the wayside signal system. The circuit connections between the track circuit networks and the line wire L₁₀ include in each case a coupling condenser and a 15 resistor. For example, at location A₂, the network is connected with the line wire L₁₀, over wire 46, resistor 47, condenser 48, and wire 49. The resistors 47, 50, and 51 at the respective locations A₂, B₂, and C₂ are provided to prevent 20 a possible false operation of the wayside signal system in the case of a broken rail. In Fig. 3, the condensers 48, 52, and 53 are each proportioned to reduce the impedance of the adjacent section of the line wire L₁₀ at the frequency of 25 the communication current. It follows that each track section of Fig. 3 is provided with a permanently closed circuit one side of which is formed by the two track rails in multiple, and the other side of which is formed by a section of the line 30 wire L₁₀. Communication current supplied to the rails of a track section flows in the closed circuit associated with that track section and is transferred to the closed circuits for the adjacent track sections in the same manner as described in 35 Figs. 1 and 2.

It is to be noted that in practicing our invention, the apparatus is located at signal locations and no additional connections to the rails other than the existing track leads are required. Furthermore, all apparatus may be housed in the 40 existing housing provided for the usual wayside signal systems.

Although we have described only three forms of apparatus embodying our invention, it is understood that various changes and modifications 45 may be made therein within the scope of the appended claims without departing from the spirit and scope of our invention.

Having thus described our invention, what we 50 claim is:

1. Trackway apparatus for use in connection with railway communication systems for communication between a point on a train and a remote point, comprising in combination with the 55 track rails, a circuit network at each of a plurality of selected points and each including a resistor connected across the track rails, said resistors each proportioned to substantially match the characteristic impedance of the track rails 60 at the frequency of the communication current, a line wire extending along the railway, and a circuit connection for each network to connect a mid-terminal of the resistor with the line wire and including a reactance proportioned to tune 65 the associated section of the line wire at the frequency of the communication current to provide a resulting communication channel effective to transmit communication current supplied to the rails at any point along the railway in both 70 directions.

2. Trackway apparatus for use in connection with railway communication systems for communication between a point on a train and a remote point, comprising in combination with the 75

- usual insulated track sections, a circuit network at each junction of adjacent track sections consisting of resistors one connected across the rails of each of the two adjacent sections and a conductor joining the mid-terminals of the resistors, said networks each proportioned to match the characteristic impedance of the track rails at the frequency of the communication current, a line wire extending along the railway, and a circuit connection for each network to connect its conductor with said line wire and including a condenser proportioned to tune the line wire at the frequency of the communication current, whereby a series of permanently closed circuits is provided with the individual circuits coupled to the adjacent circuits for transmitting communication current supplied to the rails of any one of the track sections to the rails of the adjacent sections.
20. 3. Trackway apparatus for use in connection with railway communication systems for communication between a point on a train and a remote point, comprising in combination with the usual insulated track sections and existing signal control line wires one wire extending along each section, a circuit network at each junction of adjacent track sections consisting of two resistors one connected across the rails of each of the adjacent sections and a conductor connected between the mid-terminals of the resistors, and circuit connecting means at each of said junctions to separately connect the two line wires extending in opposite directions from the junction with the conductor of the associated network to form a closed circuit for each track section which consists of the two rails in multiple as one side and the line wire as the other side, and each of said circuit connecting means including capacitance proportioned to tune each of the adjacent circuits at the frequency of a communication current and to couple the adjacent circuits.
4. Trackway apparatus for use in connection with railway communication systems for communication between a point on a train and a remote point, comprising in combination with the usual insulated track sections and existing signal control line wires one wire extending along each section, a circuit network at each junction of adjacent track sections consisting of two resistors one connected across the rails of each of the adjacent sections and a conductor connected between the mid-terminals of the resistors, means at each junction to connect the adjacent line wires and including two condensers in series, said condensers each proportioned to tune the associated line wire at the frequency of the communication current, and a circuit connection at each junction to connect the mid-terminal of said two condensers at that junction with the conductor of the network at the same junction.
5. Trackway apparatus for use in connection with railway communication systems for communication between a point on a train and a remote point, comprising in combination with the usual insulated track sections and an existing line wire extending along each section to form one side of a particular control circuit, a circuit network at each junction of adjacent track sections including a resistor connected across the rails of each of the two adjacent sections, a conductor joining the mid-terminals of the two resistors and two condensers serially interposed in said conductor; and circuit means at each junction including two condensers serially connected between the adjacent line wires and an im-

pedance element connected between the mid-terminal of these two condensers and the mid-terminal of the two condensers of the circuit network at the same junction.

6. Trackway apparatus for use in connection with railway communication systems for communication between a point on a train and a remote point, comprising in combination with the usual insulated track sections and an existing line wire extending along each section to form one side of a particular control circuit; a circuit means at each junction of the track sections connected to the adjacent two line wires and including two condensers in series, a circuit connection at each of said junctions for connecting the mid-terminal of the two condensers of the associated circuit means with the rails in multiple of each of the track sections adjacent the same junction to form a closed circuit for each track section, and a coupling condenser interposed in each circuit connection whereby communication current supplied to the rails of a section flows in the closed circuit for that section independent of the control circuit of which the associated line wire is a part and is transferred to the closed circuits of the adjacent track sections by virtue of the coupling condenser.

7. Trackway apparatus for use in connection with railway communication systems for communication between a point on a train and a remote point, comprising in combination with the usual insulated track section and a line wire extending along the section, an impedance connected across the rails at each end of the section, said impedances proportioned to match the characteristic impedance of the two rails of the section in multiple at the frequency of the communication current, a circuit connection at each end of the section to connect the mid-terminal of the associated impedance with the line wire to form a permanently closed circuit consisting of the two rails in multiple as one side and the line wire as the other side, and another impedance interposed in each of said circuit connections and said other impedances each proportioned to match the impedance of the line wire for the communication current.

8. Trackway apparatus for use in connection with railway communication systems for communication between a point on a train and a remote point, comprising in combination with the usual insulated track section and an existing line wire extending along the section to form one side of a particular control circuit, a resistor connected across the rails at each end of the section, said resistors proportioned to match the characteristic impedance of the two rails of the section in multiple at the frequency of the communication current, and a circuit connection including a condenser at each end of the section to connect the mid-terminal of the associated resistor with the line wire to form a permanently closed circuit consisting of the two rails in multiple as one side and the line wire as the other side and which circuit is independent of said control circuit, and said condensers proportioned to tune out the reactance of the line wire for the communication current.

9. Trackway apparatus for use in connection with railway communication systems for communication between a point on a train and a remote point, comprising in combination with the usual insulated track sections and existing signal control line wires one wire extending along

each section, a circuit network at each junction of adjacent track sections consisting of two resistors one connected across the rails of each of the adjacent sections and a conductor connected between the mid-terminals of the resistors, and a circuit connection for each network to connect its conductor to the two line wires extending in opposite directions from the junction and including capacitance proportioned to effect a

predetermined characteristic impedance for each of the associated line wires at the frequency of the communication current to provide a resulting communication channel effective to transmit communication current supplied to the rails of a track section to the rails of the adjacent sections. 5
